UNITED STATES PATENT OFFICE.

HARRY B. HULL, OF DAYTON, OHIO, ASSIGNOR TO DELCO-LIGHT COMPANY, OF DAYTON, OHIO, A CORPORATION OF DELAWARE.

REFRIGERATOR CABINET.

Application filed January 7, 1925. Serial No. 1,088.

The present invention relates to cabinet construction and particularly to the construction of refrigerator cabinets. One of the objects of the present invention is to simplify the construction to reduce the cost of manufacture of refrigerator cabinets and one way of carrying out this object is to provide for assembling the cabinet from unitary subassemblies.

Further objects and advantages of the present invention will be apparent from the following description, reference being had to the accompanying drawings, wherein a preferred form of embodiment of the present invention is clearly shown.

In the drawings:

Fig. 1 is a front elevation view of the improved cabinet.

Fig. 2 is a sectional view taken on line 2-2 of Fig. 1.

Fig. 3 is a perspective view showing the unitary subassemblies of the cabinet before the assembly thereof; and

Fig. 4 is an enlarged fragmentary sectional view of a portion of the cabinet shown in Fig. 2.

Referring to the drawings, one subassembly of the refrigerator cabinet 20 includes a front wall 21 having a door opening 22, and side walls 24 and 25 and a top wall 26 which are provided with inwardly extending flanges 27 which are secured by screws 28 to the back of the front wall 21. Walls 24, 25 and 26 form a U shaped member 29 and is herein shown constructed of one continuous piece of metal. It is to be understood, however, that these walls can be made of separate members and suitably connected together. The rear edges of walls 24, 25 and 26 are provided with inwardly extending flanges 30, 31 and 32.

The food compartment subassembly of the refrigerator includes a lining 34 having an opening 35 at which place the lining is flanged outwardly as at 36. The entire outside wall of the lining 34 is covered with insulating material 37 such as corkboard which is attached to the lining 34 by a cement preferably of an asphaltic waterproofing type. The upper end of the back wall of the insulating material 37 carries a wood strip 38 imbedded within the said corkboard and secured thereto by the same type of cement. The lining 34, insulating 37 and strip 38 forming a subassembly unit

40 which is adapted to be inserted from the bottom of the cabinet into the U shaped member 29, the top wall of the unit 40 engaging the wall 26 and the front wall of the unit 40 engaging the front wall 21.

After the unit 40 has been inserted within the U shaped member, said unit is clamped tightly against the front wall 21 by an auxiliary tool such as C clamps or the like. A metal pry or wedge 41 is then inserted between the flange 32 of wall 26 and the wood strip 38 each pry being secured to the strip 38 by screws 42. These wedges cooperate with the flange 32 to press the unit 40 into engagement with the front wall 21.

The bottom of the unit 40 rests upon a wood frame 44 enclosing a block of insulating material 45 which is sealed to the bottom wall of the insulating material 37 and to the frame 44. In assembling, the frame 44 is placed in position and then a coating of molten plastic material, such as an asphaltic cement or asphalt or tarry emulsion, is poured in the insulation 37 within the space surrounded by the frame 44. The insulating block 45 is then placed in position and against the plastic material and held in this position until the plastic material cools sufficiently to cause the block 45 to stick in position. Some of the plastic material will adhere to the frame 44 and thus hold same in position. While the unit 40 is still clamped against the front 21 by the auxiliary clamping means, a bracket 47 is secured by screws 48 to the frame 44 and the front 21 to maintain the lower end of the unit 40 in engagement with the wall 21. When the auxiliary clamping means is removed the unit 40 will be held tight against the wall 21 by the wedges 41 and the frame 44.

Posts 50 carrying feet 51 are secured to the frame 44 by brackets 52 and the two front posts are also secured to the wall 21 by brackets 53. The rear posts 50 carry a strip 54 for supporting a sheet metal back wall 55 which is inserted from the bottom of the cabinet and fits between the flanges 30, 31 and 32 and insulation 37. Screws 55* attach the back wall 55 to the strip 54.

When the cabinet is thus assembled the opening 35 in the lining 34 is in alignment with the opening 22 in the front 21. A door frame 58 for receiving a door 60 is carried by the front 21 and the flange 36 of the lin-

ing 34 is sealed at the frame 58 by an insulating strip 59 of rubberized cloth or the like.

It will be apparent from the foregoing description that there has been provided a refrigerating cabinet that can be manufactured at a relatively low cost, since the number of elements has been reduced and these elements can be assembled in a facile manner.

While the form of embodiment of the present invention as herein disclosed, constitutes a preferred form, it is to be understood that other forms might be adopted, all coming within the scope of the claims which follow.

What is claimed is as follows:

1. A refrigerator cabinet, comprising in combination, a cabinet wall, a laterally extending wall secured to the first wall, and provided with a shoulder, a unit including a compartment and insulation therefor adapted to be placed against said walls, and means engaging said shoulder and secured to the unit for pressing said unit against said first wall.

2. A refrigerator cabinet, comprising in combination, a cabinet wall, a U shaped member providing walls for the cabinet and secured to the first wall, one of said latter walls being provided with a shoulder, a unit including a compartment and insulation therefor, adapted to be placed within said member and against said first wall, and means engaging said shoulder and secured to the unit for pressing said unit against said first wall.

3. A refrigerator cabinet, comprising in combination, a cabinet wall, a U shaped member providing the remaining walls for the cabinet, one of said latter walls being provided with a flange for securing said member to the first wall, one of said latter walls being provided with a shoulder, a unit including a compartment and insulation therefor adapted to be placed within said member and against said first wall and means engaging said shoulder and secured to said unit for forcing said unit against said first wall.

4. A refrigerator cabinet, comprising in combination, a cabinet wall, a laterally extending wall and provided with a flange for securing same to the first wall, said laterally extending wall also being provided with a shoulder and a unit including a compartment and insulation therefor adapted to be placed against said walls and means engaging said shoulder and secured to the unit for pressing said unit against said first wall.

5. A refrigerator cabinet, comprising in combination, a cabinet wall, a laterally extending wall secured to the first wall, a unit including a compartment and insulation therefor adapted to be placed against said

laterally extending wall, and said first wall and a pry engaging said laterally extending wall and said unit for pressing said unit against said first wall.

6. A refrigerator cabinet, comprising in combination, a cabinet wall, a laterally extending wall secured to the first wall, a unit including a compartment and insulation therefor adapted to be placed against said laterally extending wall and said first wall, a pry engaging said laterally extending wall and said unit against said first wall, and means adjacent the other end of said unit adapted to be secured to the unit and said first wall for holding said other end of the unit in position.

7. A refrigerator cabinet, comprising in combination, a cabinet wall, a laterally extending wall secured to the first wall, a unit including a compartment and insulation therefor adapted to be placed against said laterally extending wall and said first wall, a pry engaging said laterally extending wall and said unit for pressing the top of the unit against the said first wall, means adhesively attached to the bottom wall of the insulation, and means for securing the first means to said first wall.

8. A refrigerator cabinet, comprising a unit including cabinet walls, a second unit including a compartment having insulation fixedly attached thereto, the second unit being adapted to be inserted into the first unit, and means for securing the second unit within the first unit.

9. A refrigerator cabinet, comprising a unit including front, side and top walls for the cabinet, a second unit including a compartment having insulation fixedly attached thereto, the second unit being adapted to be inserted through an open end of the first unit, and means for securing the second unit against the front wall.

10. A refrigerator cabinet, comprising a unit including front, side and top walls for the cabinet, a second unit including a compartment and insulation therefor adapted to be inserted through the bottom of the first unit, and means including a wedge adapted to secure the second unit to the first unit.

11. A refrigerator cabinet comprising a storage compartment having an opening, insulation for said compartment, a frame having a door opening in alignment with said compartment opening and a U shaped member having flanges secured to said frame, said member being adapted to provide a cover for opposite side walls and an end wall of said cabinet.

12. A refrigerator cabinet comprising a lining, having a door opening, insulation for said lining, an outer shell for said cabinet having a door opening in alignment with said door opening of said lining, and includ-

ing a U-shaped sheet metal member forming substantially three of the outer walls of said outer shell, and means for preventing the conduction of heat to said lining from said outer shell at said door opening.

13. A refrigerator cabinet comprising a lining having a door opening, insulation for said lining, an outer shell for said cabinet having a door opening in alignment with said door opening of said lining, and including a sheet metal member bent to form substantially all of a plurality of the outer walls of said outer shell, and means for preventing the conduction of heat to said lining from said outer shell at said door openings.

14. A refrigerator cabinet comprising a lining having a door opening, insulation for said lining, an outer shell for said cabinet having a door opening in alignment with said door opening of the lining and including a U-shaped sheet metal member forming substantially three of the outer walls of said outer shell, and provided with a flange directed toward said door opening, and means for preventing the conduction of heat to said lining from said outer shell at said door opening.

In testimony whereof I hereto affix my signature.

HARRY B. HULL.
